FOUNDRY FLASK

William J. Spensley, Dubuque, Iowa, assignor to
 The Adams Company, Dubuque, Iowa, a corpora-
 tion of Iowa

Application October 19, 1942, Serial No. 462,554

8 Claims. (Cl. 22—107)

This invention relates to foundry flasks and has special reference to flasks of the type adapted to be lifted off the mold and to improved operators for opening and closing the flask.

The principal object of the invention is the provision of a flask of the type described wherein improved means is provided for opening and closing the flask in which the movement of the flask sections is positively effected by cam mechanism and the flask is locked in closed position by cam means, and further contemplates construction in which the operating mechanism includes guides located in the open outside the perimeter of the flask for maintaining the flask sections in alignment at all times.

Another object is the provision of an operator wherein the sections are connected and actuated at a plurality of points spaced along the abutting corners of the flask so as to provide smooth operation and positive locks spaced along the corner and joining the sections of the flask.

A further object of the invention is the provision in a flask of the type described of a novel cam mechanism for opening and closing the flask arranged for quick operation and constructed so that it does not become fouled by accumulations of sand.

Other objects and advantages will appear from the following description and the accompanying drawings, in which—

Figure 1 is a side elevational view of a flask embodying my invention;

Fig. 2 is a top view thereof;

Fig. 3 is an enlarged top view of the corner showing the operating mechanism in the closed position;

Fig. 4 is a view similar to Fig. 3 showing the operating mechanism in open position;

Fig. 5 is a section taken substantially on the line 5—5 of Fig. 4;

Fig. 6 is a side elevational view partly in section taken on the line 6—6 of Fig. 4, and

Fig. 7 is a fragmentary view of the cam mechanism taken on the line 7—7 of Fig. 6.

The invention contemplates a flask of any conventional form and is herein shown as embodied in a flask of the type having the usual cope 8 and drag 9, in this instance formed of wood, though the invention can be embodied in a metal structure with equal facility. In accordance with the usual practice, the flask has the conventional vertical guides designated generally by the numerals 11 and 12, the specific features of which form no part of the present invention and consequently will not be specifically described

since they are common in the art. Likewise the drag has its upper and lower edges finished by conventional metal edging strips as indicated at 13 and 14 and the cope has similar strips 15 and 16 in accordance with the usual practice. Both the cope and the drag are divided at opposed corners into two sections indicated generally by the numerals 17 and 18, the section 18 comprising upstanding walls 19 and 21 rigidly joined to form a corner as indicated at 22, and likewise the section 17 includes upstanding walls 23 and 24 rigidly joined at a corner 25. The walls 19 and 23 are arranged to abut at their free ends to form a separable corner as indicated at 26, and likewise the walls 21 and 24 abut at their ends to form a separable corner 27.

The invention contemplates improved means for connecting the cope and the drag sections at the corners 26 and 27 so as to allow these corners to open and thereby expand the flask so that it may be lifted from around the mold. This means comprises an operating means located at the abutting corners of both the cope and the drag, and since the principle of these operating means is identical, it will be sufficient to describe a structure and mode of operation of only one.

Adjacent the corner formed by the abutting ends of the walls 21 and 24 of the cope, at which end the walls are beveled as shown at 28 and 29 (Fig. 4) a bracket 31 is attached to the outer surface of the wall 21 as by means of bolts and nuts 32 and screws 33. This bracket has a pair of spaced ears 34 and 35 projecting outwardly therefrom with the faces thereof in this instance being in substantial parallelism with the ends 28 and 29 of the walls. Positioned in the ears 34 and 35 are rods 36 and 37 which extend diagonally across the corner, as will best be seen from Figs. 4 and 6, the rods in this instance being threaded at one end as indicated at 38 for the reception of nuts 39 threaded thereon to rigidly retain the rods in the ears 34 and 35.

Attached to the outer surface of the wall 24 adjacent the corner is a bracket 41 secured against the wall by means of bolts 42 and screws 43. This bracket has outwardly disposed ears 44 and 45 in substantially the same plane as the ears 34 and 35, the ears being provided with bores for the snug reception of the rods 36 and 37 to provide guides for these rods so that as the rods slide through the guides, the ends of the two walls are maintained in alignment. The ears 44 and 45 are formed by upstanding ribs, part of which project in parallelism with the rods 36 and 37 as indicated at 46 and 47 (Fig. 6), the upper

and lower surfaces of which form ways 48 and 49 for a purpose presently to be described. The rib portions 46 and 47 are interconnected by spaced vertical walls 51 and 52 between which a handle 53 is positioned and pivoted on a bolt 54 passing through the walls for pivotal movement of the handle thereon. The handle has an outwardly disposed loop 55 adapted to be grasped by the hand of the user in manipulating the handle and also has an upwardly disposed cam follower 56 rigid therewith and a downwardly disposed cam follower 57 likewise rigid with the handle as will best be seen from Fig. 5, from which it will be seen that as the handle is rotated about the pin 54 in an upward direction the follower 56 moves inwardly toward the wall 24, and the follower 57 moves outwardly, and upon downward movement of the handle 55 the reverse action occurs. Positioned on the rod 36 and in sliding engagement with the surface 48 is a cam member 58 having a boss 59 into which the end of the rod 36 is threaded, a bearing face 61 abutting against the surface 48 so as to slide thereover upon relative movement of the two ends of the walls and spaced opposed cam surfaces 62 and 63 adapted to receive therebetween the cam follower 56. These cam surfaces are so spaced and sloped that the cam follower 56 moves therealong in response to rotation of the handle and when the handle is raised acts primarily against the surface 62 to cause the rod 36 to move with respect to the guide 44 in a direction to bring the abutting ends of the walls together. These surfaces are substantially parallel throughout the greater portion of their length, but the cam surface 62 diverges as shown at 64 adjacent its inner end to provide a cam surface approaching a flat stop so that the follower 56 moves onto this flat stop and it is therefore impossible for the cam to drive the follower outward in response to pressure within the flask, that is, by opening pressure applied against the walls 21 and 24. This cam surface therefore acts as a lock to lock the walls in the closed position.

Positioned on the rod 37 and against the slide surface 49 is a cam 65 likewise having a boss 66 for attachment to the rod 37 and cam surfaces 67 and 68 for the close reception therebetween of cam follower 57, the cam surfaces 67 and 68 sloping in diverging relation with respect to the surfaces 62 and 63 as will be seen from a comparison of Figs. 3 and 7, so that as the handle 55 is moved upwardly, the follower 57 moves along the surface 67 moving the rod 37 in the same direction to draw the ends of the walls together. In this instance the cam surface 68 has a portion 69 opposite the follower to prevent the cam from driving the follower in response to pressure within the flask tending to open the corner, this cam surface thus cooperating with the cam portion 64 to lock the corner in the open position. It will be seen that when the handle 55 is moved downwardly the follower 56 moves along the cam surface 63 and the follower 57 moves along the cam surface 67 to force the two ends of the walls apart to the open position.

Attention is directed to the fact that the corners are positively driven from the open to the closed position and from the closed to the open position, which is an important feature of the invention because of the fact that in many instances the flask tends to stick to the sides of the molds and must be forcibly separated therefrom. This mechanism provides cam means through

which a powerful force can be applied at the corners for the purpose of separating the walls of the flask from the mold, and the application of this force can be controlled since the handle is manually moved between its positions. Another important feature of the invention is the fact that when the corner is moved to the closed position, the cam acts to lock the operating means and the corner in this position so that it cannot be released by the operation of squeezing or jolting the sand in the flask. Another important feature of the invention is the fact that the rods 36 and 37 and the guides are located outside the perimeter of the flask so that the sand falls freely away from these parts and therefore will not bind or plug the mechanism. Likewise the cam mechanism is so arranged that the cam openings are at all times shielded from the entry of sand which might tend to impair or interfere with their operation, and the fact that the two walls are positively guided at the corner in their movement by operation of the guides 44 and 45 and the rods 36 and 37 which positively prevent misalignment. It will also be noted that these rods and guides are spaced so that the rod 36 falls near the top of the cope or the drag and the rod 37 falls near the bottom thereof so that the walls are moved from points spaced along the corner and the force being applied to these rods tends to provide uniformity in operation and prevent distortion of the flask.

I claim:

1. The combination in a foundry flask of upstanding walls having ends separably abutting to form a corner for said flask, a plurality of parallelly disposed spaced rods rigidly secured to the outer surface of one wall adjacent said corner and extending diagonally across said corner, a handle attached to the outer side of the other wall adjacent said corner pivoted on an axis parallel to said rods, cams positioned on each of said rods adjacent said handle, and cam followers driven by said handle operative on said cams to move the ends of the walls apart upon movement of the handle in one direction and draw the ends together upon movement of the handle in the opposite direction, said cams having cam portions for imparting opening and closing movement, and a cam portion for locking the ends in closed position.

2. The combination in a foundry flask of upstanding walls having ends separably abutting to form a corner for said flask, a plurality of parallelly disposed spaced rods rigidly secured to the outer surface of one wall adjacent said corner, and extending diagonally across said corner, guides rigidly secured to the outer surface of the other of said walls adjacent said corner for the passage of said rods to maintain said ends in alignment during relative movement thereof, a handle attached to said other wall between said rods and beyond said guides, on an axis parallel to said rods, cam followers projecting from said handle toward said rods, and oppositely disposed cams on said rods engaging said followers to move said rods longitudinally in one direction upon movement of said handle in one direction to separate said ends and open said flask and move said rods in the opposite direction upon rotation of said handle in the opposite direction to bring said ends together and close said flask.

3. The combination in a foundry flask of upstanding walls having ends separably abutting to form a corner for said flask, a plurality of parallelly disposed spaced rods rigidly secured to the

outer surface of one wall adjacent said corner and extending across said corner, guides rigidly secured on the outer surface of the other side wall adjacent said corner for the passage of said rods to maintain said ends in alignment during relative movement thereof, a handle attached to said other wall between said rods and beyond said guides on an axis parallel to said rods, cam followers projecting from said handle toward said rods, and oppositely disposed double acting cams on said rods engaging said followers, each of said cams having sliding surfaces for imparting longitudinal movement to said rods in opposite directions to move said ends toward and away from each other upon rotation of said handle and also having a cam surface for locking said ends in closed position.

4. The combination in a foundry flask of upstanding walls, having ends separably abutting to form a corner for said flask, a bracket attached to the outer surface of one of said sides adjacent said corner having a rod projecting across said corner in spaced relation thereto, a guide on the other of said walls adjacent said corner cooperable with said rod to maintain said ends in alignment during opening and closing movement, a lever pivoted on said other side on an axis parallel to said rod for vertical rotation with respect to said flask, a cam member on said rod having spaced vertically disposed cam surfaces positioned at an angle other than 90° with respect to said rod, and a cam follower on said lever positioned between said cam surfaces for moving said rod longitudinally of the guide to force the ends of the walls apart upon rotation of the lever in one direction and to force the ends together upon rotation of the lever in the opposite direction.

5. The combination in a foundry flask of upstanding walls having ends separably abutting to form a corner for said flask, a bracket attached against the outer surface of one of said sides adjacent said corner having a rod projecting across said corner in spaced relation thereto, a guide on the other of said walls adjacent said corner cooperable with said rod to maintain said ends in alignment during opening and closing movement, a lever pivoted on said other side adjacent said corner on an axis parallel to said rod for vertical rotation with respect to said flask, the same member on said rod having spaced vertically disposed cam surfaces positioned at an angle other than 90° with respect to said rod, and a cam follower on said lever positioned between said cam surfaces for moving said rod longitudinally of the guide to force the ends of the walls apart upon rotation of the lever in one direction and to force the ends together upon rotation of the lever in the opposite direction, said cam surfaces having cam portions for imparting opening said closing movement to said ends, and one of said cam surfaces having a cam portion for locking the ends in closed position.

6. The combination in a foundry flask of upstanding walls having ends separably abutting to form a corner for said flask, a bracket at-

tached against the outer surface of one of said sides having parallelly disposed spaced rods projecting across said corner and fixed to said bracket, cam members on said rods having spaced vertically disposed cam surfaces positioned at an angle other than 90° with respect to the axis of said rods, a handle pivoted on the other of said walls adjacent the corner and disposed between said cam members, and cam followers on said handle projecting between the cam surfaces of said cam members for forcing the ends of said walls apart upon rotation of the handle in one direction and for drawing said ends together upon rotation of the handle in the opposite direction.

7. The combination in a foundry flask of upstanding walls having ends separably abutting to form a corner for said flask, spaced upper and lower ends rigidly secured to the outer surface of one wall adjacent said corner and extending across said corner exteriorly thereof, a handle attached to the outer side of the other wall adjacent said corner pivoted on an axis parallel to and between said rods for rotation in a vertical plane, a double acting cam member on each of said rods adjacent said handle comprising a member of U-shaped cross-section having spaced vertically disposed cam surfaces, the member attached to said upper rod having the open end 20 of the U downwardly disposed and the member attached to the lower rod having the U upwardly disposed, and cam followers actuated by said handle and disposed between said cam surfaces of said members to move said cams and rods in 25 either of two directions dependent upon the direction of rotation of said handle and thereby move the corners toward and away from each other to open and close the flask.

8. The combination in a foundry flask, of upstanding walls having ends separably abutting to form a corner for said flask, a bracket attached to one of said walls adjacent said corner having spaced upper and lower rods rigidly secured thereto extending across said corner, a second bracket attached to the other of said walls having guide openings for the passage of said rods and having guide bearing surfaces, a handle attached to said second bracket intermediate said guide surfaces and pivoted on an axis parallel to said rods for rotation in a vertical plane, a double acting cam member on each of said rods having bearing guide surfaces cooperating with the guide surfaces of said bracket, said cam members comprising a member of U-shaped cross-section having spaced vertical cam surfaces, the members being disposed with the open ends of the U facing said lever, and cam followers actuated by said handle and disposed between said cam surfaces of said members, said followers substantially filling the space between said spaced vertical cam surfaces and acting to move said cams and said rods in a direction to close said flask when said handle is moved downwardly and to open said flask when the handle is moved upwardly.

WILLIAM J. SPENSLEY.
